COOLING APPARATUS

Ernest F. Miller, Prospect Park, Pa., assignor to
Westinghouse Electric & Manufacturing Com-
pany, East Pittsburgh, Pa., a corporation of
Pennsylvania

Application April 20, 1934, Serial No. 721,475

8 Claims. (Cl. 62—152)

My invention relates to refrigerating apparatus, more particularly to a liquid circulating system for refrigerating apparatus of the steam or vapor jet type, and it has for an object to provide improved apparatus of the character set forth.

A further object is to provide, in refrigerating apparatus of the vapor jet type embodying an evaporative condenser, improved means for removing condensate from the condenser and for delivering said condensate and unevaporated water for effecting evaporative cooling of the condenser.

A further object is to provide means for readily draining the liquid from the apparatus to prevent freezing thereof in cold weather or for other purposes.

In accordance with my invention, I use the condensate formed in the condenser to provide a supply of liquid to effect evaporative cooling of the condenser, preferably as a spray for wetting the air-cooled surfaces of the condenser. I also drain the liquid which is not evaporated and add the same to the condensate before supplying the same to said spray.

A single pump serves to remove condensate from the condenser and to deliver the condensate and additional water under pressure to the spray. The unevaporated water is returned to the inlet of the pump, a float valve controlling the flow thereof to maintain a given submergence on the inlet of said pump, while all condensate is permitted to flow uncontrolled to said inlet.

I also provide means for supplying condensate from the condenser to the evaporator to replace liquid therein. I withdraw this condensate from the stream of condensate flowing to the inlet of the pump before the unevaporated spray water is added thereto, whereby only pure condensate is admitted to the evaporator.

To drain the water from the apparatus, I provide a drain conduit connected to each of the several pressure regions of the apparatus and having a single discharge valve, preferably manually operated, so that the water may be drained by opening the one discharge valve. A check valve is provided in each connection except that communicating with the region containing the highest pressure when the apparatus is in operation. The latter pressure, communicated through the drain conduit, closes the check valves to isolate the several pressure regions from each other during operation.

The above and other objects are effected by my invention as will be apparent from the fol-

lowing description and claims taken in connection with the accompanying drawings, forming a part of this application, in which:

The single figure is a diagrammatic view, in elevation, of apparatus embodying my invention.

Referring to the drawing in detail, I show an evaporator 10, which also serves, in this case, to cool air directly. The evaporator includes a casing 11, upper and lower headers 12 and 13, 10 and cross-finned tubes 14 extending between said headers and providing free communication therebetween. The interior of the headers and the tubes constitutes the evaporating chamber. The casing 11 is formed with an inlet 15 and an outlet 16 for the passage of fluid to be cooled, such as air, in contact with the outer surfaces of the tubes.

A manifold 17 and a plurality of spray nozzles 18 mounted thereon are provided in the upper header 12 and arranged to direct a spray of refrigerant liquid particles into the upper open ends of the tubes 14. The refrigerant is usually water, which liquid will be referred to hereinafter without restricting the invention thereto. An ejector or thermal compressor 19 is provided to effect a reduced pressure within the evaporating chamber by removing vapor therefrom, and has its suction inlet 21 connected, in the illustrated embodiment, to the lower header 13 through a conduit 22. Vapor for motivating the ejector, usually steam, is supplied to the ejector through a conduit 23.

A condenser 24 is connected to the outlet of the ejector for condensing the vapor discharged therefrom, including the vapor withdrawn from the evaporating chamber and the expended motive fluid. The condenser includes headers 25 and 26, and tubes 27 extending therebetween. The headers and tubes contain the vapor to be condensed, the header 25 being connected to the ejector outlet. Suitable means (not shown) are provided for removing air and non-condensable gases from the condensing space of the condenser. The cooling fluid, which is preferably air, is circulated in contact with the outer surfaces of the tubes by a fan 28. Viewing the apparatus as seen on the drawing, the direction of flow of the cooling air is either forwardly or rearwardly. To increase the cooling effect, I provide evaporative cooling of the condenser tubes. Nozzles 29, carried by upper and lower manifolds 31, are provided to spray water into the circulating air stream and onto the outer surfaces of the tubes. The nozzles are arranged in

staggered relation, and each nozzle provides a divergent triangular spray which is complementary to the adjacent sprays. The water is evaporated by the circulating air, thereby augmenting the cooling effect available for condensing the vapor within the tubes.

The water circulating system provides circulation of water through the evaporator 10, a supply of condensate from the condenser 24 to the evaporator to replace evaporated water, and delivery under pressure to the condenser spray nozzles 29 of the remaining condensate and of unevaporated condenser spray water. The lower header 13 of the evaporator 10 is formed with a drain outlet 32 connected, through a conduit 33, to the inlet of a water circulating pump 34. The outlet of said pump is connected through a conduit 35 to the nozzle manifold 17.

The condensate formed in the condenser collects in the headers 25 and 26 which are connected to a drain conduit 36, through which the condensate flows downwardly by gravity. The conduit 36 is connected to the conduit 33, through parts presently described, for the purpose of supplying make-up water to the evaporator; that is, water for replacing that evaporated in the evaporator. The conduit 36 has a branch 36a which is connected to a float chamber 37. A float valve 38, actuated by a float member 39 within said chamber, controls the flow of liquid from the branch conduit 36a into the float chamber. The latter is connected through a conduit 41 with the conduit 33 for supplying liquid thereto. The float valve 38 serves to control the flow of condensate to the conduit 33 to maintain a predetermined level of liquid within the float chamber 37, the valve decreasing the flow of condensate as said level tends to rise and increasing said flow as the level tends to drop. The upper part of the float chamber 37 is connected to the evaporator, at any suitable point such as the header 12, through a vent pipe 42. The same level of liquid is maintained, therefore, within the conduit 33 and the float chamber 37.

The conduit 36 is also connected, through a branch 36b, to a conduit 42', which conveys the remaining condensate to the inlet of a circulating pump 43. The pumps 34 and 43 may be gear pumps, as shown, and are desirably driven by a common source of power, such as an electric motor 40. The pump 43 discharges water under pressure to a conduit 44, which conveys the same to the nozzle manifolds 31. Only a small portion of the water sprayed onto the condenser tubes at one time is evaporated, so that it is necessary to recirculate the unevaporated water. This water collects in a sump 45, from which it flows through a conduit 46, a float chamber 47, a conduit 48, a float chamber 49, and a conduit 51, to the conduit 42', in which it is added to the condensate flowing to the pump 43.

Within the float chamber 47 is a float valve 52 having a float member 53 controlled by the level of liquid in the float chamber. The purpose of the float valve 52 is to prevent the admission of air from the atmosphere to the condenser through the water-circulating conduits in the event that the quantity of unevaporated spray water in the float chamber 47 is insufficient to immerse the end of the conduit 48. As the water level in the float chamber 47 drops, due to any such insufficiency, the float member 53 moves the valve 52 in closing direction, thereby preventing 75 drop in water level below a predetermined point.

A drain conduit 54 is connected to the upper portion of the float chamber 47, to drain off excess water when the quantity of unevaporated spray water exceeds the quantity required by and admitted to the pump 43.

Within the float chamber 49, there is provided a float valve 55, the purpose of which is to limit the admission of unevaporated condenser spray water to the conduit 42 to an amount which, together with the condensate flowing thereto from the condenser does not exceed the capacity of the pump 43, thereby assuring that all condensate will be removed from the condenser. The float valve 55 includes a float member 56 responsive to the level of liquid in the float chamber 49, which level is on the down-stream side of the valve 55. Upon drop in water level, the valve 55 moves in opening direction to admit more water, tending to maintain said level substantially constant. The upper portion of the float chamber 49 is connected through a vent pipe 57 to the header 25, so that the liquid within the conduit 36 and the float chamber 49 will be at the same level. It will be apparent that all condensate formed in the condenser and not supplied to the conduit 33 may flow unrestricted to the pump 43. Any increase in the quantity of condensate will tend to raise the level of the liquid in the float chamber 49 and restrict the admission of unevaporated condenser spray water.

The operation of the above-described apparatus, which will be apparent from the above description, is as follows: The water sprayed from the nozzles 18 in the evaporator 10 flows downwardly through the interior of the tubes 14, a portion of said water being evaporated by the heat extracted from the air flowing over the tubes. The vapor is withdrawn from the evaporator by the ejector 19 and discharged, together with the expended motive fluid, into the condenser 24. The unevaporated water collecting in the lower header 13 flows by gravity through the conduit 33 to the pump 34, by which it is recirculated through the conduit 35 to the nozzles 18. Due to the continual evaporation of a portion of the water, the total quantity in the circuit just described would tend to decrease, thereby lowering the water level in the conduit 33 and the float chamber 37. The float member 39 responds to the drop in water level by opening the valve 38 to admit a quantity of condensate from the condenser 24 which is sufficient to maintain said water level substantially constant and which replaces the water evaporated within the tubes 14.

The remainder of the condensate from the condenser flows unrestricted through the conduits 36, 36b, and 42' to the pump 43, by which it is circulated through the conduit 44 to the spray nozzles 29. From the latter it is directed onto the exterior surfaces of the condenser tubes 27 to provide evaporative cooling of said tubes. Inasmuch as the quantity of water circulated by the pump 43 is considerably in excess of the quantity of condensate formed within the condenser, the level of liquid within the conduit 36 and the float chamber 49 will tend to drop. The float member 56 is responsive to the drop in level and opens the valve 55 to admit such quantity of unevaporated spray water as is required to maintain substantially the same level, thereby providing the required amount of water to be circulated by the pump 43. When the total quantity of unevaporated spray water returned through the conduit 46 exceeds the capacity of the pump 43, the 7

valve 55 regulates the quantity which is admitted to the pump 43 in accordance with the capacity thereof and the excess water overflows from the float chamber 47 into the drain conduit 54, the valve 52 being wide open in this case.

When the supply of unevaporated spray water or other supply of additional liquid is less than the capacity of the pump 43, the valve 52 will serve to prevent the entrance of air into the conduit 48 as described above and the valve 55 will be wide open to permit all of the liquid to flow to the pump. In this case, a quantity of water less than the capacity of the pump 43 is circulated by the pump. In an installation in which the quantity of unevaporated spray water or other spray of additional liquid, taken together with the condensate flowing to the pump, is always less than the capacity of the pump 43, the valve 55 may be dispensed with, and in an installation in which it is always greater than the capacity of the pump 43, the valve 52 may be omitted. It will be apparent, therefore, that I have made provision against flooding the condenser by the admission of an excess quantity of water to the inlet of the pump and that I have also made provision against the admission of air into the condenser upon a deficiency in supply of unevaporated spray water or other liquid.

It will be noted that the condensate which is supplied to the evaporator as make-up to replace evaporated liquid, is withdrawn through the conduit 36a before the portion of the condensate flowing to the pump 43 through the conduit 36b is mixed with the unevaporated spray water. In this way, the impurities and dissolved air which the unevaporated spray water may have acquired in the spray is prevented from entering the evaporator.

The apparatus described may be used for any suitable application where air cooling or other cooling is required; for example, it may be installed on a railway passenger car for cooling the air therein.

A further feature of my invention resides in the provision of means for readily draining the water or other liquid from the system, in order to prevent freezing and damage to the apparatus in cold weather. This provision is particularly applicable to passenger railway cars which move between widely varying climates. I provide a drain conduit 62, which discharges into the drain conduit 54 and which is provided with a single discharge valve 63. Branch conduits 57', 58, 59, 60, and 61 connect the conduits 35, 33, 42, and 44, and the float chamber 47, respectively, with the drain conduit 62, the points of communication with the latter conduits being adjacent the lowermost points thereof so that water may readily flow therefrom by gravity. In each of the branch conduits 57', 58, 59, and 61, I provide a check valve 64 which permits downward flow of water into the drain conduit 62, but which prevents upward flow of water. The branch conduit 60 communicates with the conduit 62 which contains the highest pressure within the apparatus when it is in operation, and no check valve is placed in this branch conduit. When the apparatus is in operation, the maximum pressure of the system in the conduit 44 is communicated through the branch conduit 60 to the drain conduit 62 and imposed on the check valves to close the same, thereby isolating the several pressure regions represented by said conduits from each other. In this case, the discharge valve 63 is closed. When operation of the apparatus is discontinued, the

pressures within the system are released and all of the check valves are free to open. If the discharge valve 63 is opened in this case, water may flow by gravity from the several portions of the apparatus through the respective branch conduits into the drain conduit 62, and through the discharge valve 63 into the drain conduit 54.

It will thus be seen that I have provided a simple drain arrangement whereby the apparatus may be completely drained of liquid by the opening of a single valve.

While I have shown my invention in but one form, it will be obvious to those skilled in the art that it is not so limited, but is susceptible of various changes and modifications without departing from the spirit thereof, and I desire, therefore, that only such limitations shall be placed thereupon as are imposed by the prior art or as are specifically set forth in the appended claims.

What I claim is:

1. The combination with a condenser, of a pump having its inlet disposed at a level below the condensate outlet of said condenser and connected thereto, whereby condensate flows by gravity from said condensate outlet to the inlet of said pump, means connected to the outlet of said pump and utilizing the liquid discharged therefrom to provide evaporative cooling of said condenser, and means for supplying additional liquid to the inlet of said pump including means responsive to the head of liquid on the pump inlet for regulating the supply of said additional liquid to maintain a given submergence on said pump.

2. In vapor jet refrigerating apparatus, the combination of an evaporator, an ejector for removing vapor from said evaporator to effect cooling by evaporation of liquid therein, an air cooled condenser for condensing the gaseous fluid discharged by the ejector, a pump for withdrawing condensate from the condenser and for spraying the same onto the air cooled surfaces of the condenser, drain conduit means communicating with the discharge side of said pump, a single valve controlling discharge of liquid therefrom, a connection between the evaporator and the drain conduit means, a connection between the inlet side of the pump and the drain conduit means, and means responsive to fluid pressure developed by said pump for closing communication through said connections.

3. In vapor jet refrigerating apparatus, the combination of an evaporator, an ejector for removing vapor from said evaporator to effect cooling by evaporation of liquid therein, an air cooled condenser for condensing the gaseous fluid discharged by the ejector, a pump for withdrawing condensate from the condenser and for spraying the same onto the air-cooled surfaces of the condenser, drain conduit means communicating with the discharge side of said pump, a single valve controlling discharge of liquid therefrom, a connection between the evaporator and the drain conduit means, a connection between the inlet side of the pump and the drain conduit means, and a check valve in each of said connections arranged to permit flow into said drain conduit means and to prevent flow in the opposite direction, said valves being closed in normal operation by the pump discharge pressure.

4. The combination of an evaporative condenser, means including a mechanical pump for spraying liquid onto the air cooled surfaces of said condenser, said pump having its inlet connected to the condensing space of the condenser

and being effective to remove condensate therefrom, and means for delivering unevaporated spray water to the inlet of said pump at sub-atmospheric pressure, said pump imposing sufficient pressure on said condensate and unevaporated spray water for spraying the same against atmospheric pressure.

5. The combination with an evaporative condenser, of means for directing liquid onto the air cooled surfaces of the condenser to provide evaporative cooling, a mechanical condensate removal pump having its inlet connected to the condensing space of the condenser for receiving condensate therefrom, means for delivering unevaporated liquid from said air cooled surfaces to the inlet of the pump at sub-atmospheric pressure, and means responsive to the head of liquid on the inlet of the pump for controlling the flow of said unevaporated liquid thereto, said condensate pump being effective to deliver said condensate and unevaporated liquid under pressure to said first-mentioned means.

6. The combination with an evaporative condenser, of means for directing liquid onto the air cooled surfaces of the condenser to provide evaporative cooling, a mechanical condensate removal pump having its inlet connected to the condensing space of the condenser for receiving condensate therefrom, means for delivering unevaporated liquid from said air cooled surfaces to the inlet of the pump at sub-atmospheric pressure and mixing the same with the condensate, and means for extracting condensate at a point ahead

of the point of mixture so as to provide a supply of pure condensate, said condensate pump being effective to deliver said condensate and said unevaporated liquid under pressure to said first-mentioned means.

7. The combination with an air cooled evaporative condenser, of a pump for withdrawing condensate from the condenser and for delivering liquid under pressure for supplying the air cooled surfaces of the condenser, drain conduit means communicating with the discharge side of said pump, a single valve controlling discharge of liquid therefrom, a connection between the inlet side of the pump and the drain conduit means, and means responsive to fluid pressure developed by said pump for closing communication through said connection.

8. The combination with an air cooled evaporative condenser, of a pump for withdrawing condensate from the condenser and for delivering liquid under pressure for supplying the air cooled surfaces of the condenser, drain conduit means communicating with the discharge side of said pump, a single valve controlling discharge of liquid therefrom, a connection between the inlet side of the pump and the drain conduit means, and a check valve in said connection arranged to permit flow into said drain conduit means and to prevent flow in the opposite direction, said check valve being closed in normal operation by the pump discharge pressure.

ERNEST F. MILLER.
